(57) **CLAIM**

The ornamental design for an automobile body and/or other replica, as shown and described.

DESCRIPTION

FIG. 1 is a right, front perspective view of an automobile body and/or other replica showing our new design;
FIG. 2 is a right, rear perspective view thereof;
FIG. 3 is a front elevation view thereof;
FIG. 4 is a rear elevation view thereof;
FIG. 5 is a right side elevation view thereof;
FIG. 6 is a top plan view thereof; and,
FIG. 7 is a left side elevation view thereof.
The broken line portions of the automobile body and/or other replica shown throughout the drawing views are for illustrative and environmental purposes that form no part of the claimed design.

1 Claim, 7 Drawing Sheets
